United States Patent Office

Des. 178,551

Patented Aug. 14, 1956

178,551

SHOE

Rubin Sherman, Lowell, Mass.

Application December 1, 1954, Serial No. 33,355

Term of patent 7 years

(Cl. D7—7)

Fig. 1

Fig. 2

Figure 1 is a side view and Figure 2 is a bottom plan view of a shoe showing my new design.

The dominant feature of the invention resides in the sole portion.

I claim:

The ornamental design for a shoe, as shown and described.
